United States Patent Office

Des. 230,329

Patented Feb. 5, 1974

230,329

SHAVER

Robert A. Mockovak, Newtown, Conn., assignor to Sperry
Rand Corporation, New York, N.Y.

Filed May 30, 1972, Ser. No. 258,233

Term of patent 14 years

Int. Cl. D28—03

U.S. Cl. D95—3 A

Fig. 1

Fig. 2.

Fig. 3.

Fig. 4

Fig. 5.

Fig. 6.

Fig. 7

FIG. 1 is a perspective view of a shaver showing my new design;

FIG. 2 is a front elevational view;

FIG. 3 is a right side elevational view;

FIG. 4 is a top plan view;

FIG. 5 is a rear elevational view;

FIG. 6 is a bottom plan view; and

FIG. 7 is a bottom plan view showing a modified switching means.

In FIGS. 1, 2, 4, and 5 it is understood that the cutter teeth omitted for convenience of illustration are continuous in the paths indicated by the dot-dash lines.

I claim:

The ornamental design for a shaver, substantially as shown and described.
